CLAIM

The ornamental design for a bottle lid, as shown and described.

DESCRIPTION

FIG. 1 is a front elevational view of a bottle lid, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top perspective view thereof;

FIG. 8 is a bottom perspective view thereof;

FIG. 9 is a perspective view of the handle portion of the bottle lid of FIG. 1, shown separated from the body portion; and,

FIG. 10 is a perspective view of the body portion of the bottle lid of FIG. 1, shown separated from the handle portion.

1 Claim, 5 Drawing Sheets
